[57] **CLAIM**

The ornamental design for a battery powered spark igniter for a gas grill, as shown.

DESCRIPTION

FIG. 1 is a perspective view of a battery powered spark igniter for a gas grill showing my new design;

FIG. 2 is a top plan view thereof;

FIG. 3 is a side elevational view thereof;

FIG. 4 is a front elevational view thereof;

FIG. 5 is a side elevational view of the opposite side of FIG. 3;

FIG. 6 is a bottom plan view thereof; and,

FIG. 7 is a rear elevational view thereof.
